(57) **CLAIM**

The ornamental design for a female component for environmentally sealed, compact, high current, three-conductor connector housing system, as shown and described.

DESCRIPTION

FIG. 1 is a front view of the female component for environmentally sealed, compact, high current, three-conductor connector housing system;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a front, top perspective view thereof; and,

FIG. 8 is a back, bottom perspective view thereof.
